UNITED STATES PATENT OFFICE.

ANDREW TAYLOR, OF GOLDFVILLE, SOUTH CAROLINA, ASSIGNOR TO CLINTON CAM COMPANY, OF CLINTON, SOUTH CAROLINA, A CORPORATION OF SOUTH CAROLINA.

BOBBIN-SKEWER.

1,239,138.

Specification of Letters Patent. Patented Sept. 4, 1917.

Application filed February 2, 1916. Serial No. 75,706.

To all whom it may concern:

Be it known that I, ANDREW TAYLOR, a citizen of the United States of America, and a resident of Goldville, county of Laurens, 5 State of South Carolina, have invented certain new and useful Improvements in Bobbin-Skewers, of which the following is a full and clear specification.

This invention relates to that class of 10 skewers employed for holding bobbins in roving machines. In this type of skewer, as is well known, the skewers are journaled vertically in a creel, the upper end of the skewer being held loosely in a top bar and 15 the lower pointed end of the skewer being provided with a top or point, bearing in a cup or socket formed in or mounted on the bearing rail of the creel. The bobbin is slipped down over the skewer and rests upon 20 an annular shoulder positioned at the lower end of the skewer. An objection to this common form of skewer as now made is that when the skewer carrying the bobbin is accidentally dropped on the floor, as frequently 25 happens in handling the bobbin, the bearing point is broken and the wooden shaft of the skewer is sometimes shattered. It is the object of my invention to provide the lower or bearing end of the skewer with 30 a device which will prevent such injury to the skewer when a loaded skewer is accidentally dropped.

In the drawings—

Figure 1 is a side elevation of a skewer 35 provided with my improved point;

Fig. 2 is a vertical sectional view of the lower end of the skewer; and

Fig. 3 is a plan view of the skewer point detached.

Referring to the drawings annexed, *a* is the usual wooden staff of the skewer. At its lower end, this staff is reduced in diameter to form a tenon *b* and a downwardly-facing, beveled, annular shoulder *c*. A metal socket 40 *d* incloses the tenon *b* snugly and is fastened thereto by a screw *e* passed through a hole in

the socket and screwed transversely into the tenon. Formed integral with the lower end of this socket is a disk *f* which is sufficiently large in diameter to form a support for the 50 bobbin spool. Depending centrally from the disk *f* is an integral bearing point *g*, and formed integral with the socket *d* is a plurality of radial vertical ribs *h* which bear against the inner face of the bobbin spool 55 and serve to center the same on the disk *f*.

By thus fastening the staff in a metal socket carrying an integral supporting disk and an integral bearing point, it will be seen that likelihood of injury when a loaded 60 skewer is dropped point-downwardly on the floor is practically eliminated. The socket and its integral parts are formed of metal so that fracture thereof is practically out of the question. The clasping of the lower end 65 of the staff in a metal socket prevents splitting and shattering of the staff, as is obvious, and the use of radial ribs as a means of centering the bobbin is advantageous as compared with a continuous annular shoulder, 70 in that the danger of foreign substances lodging between the bobbin spool and the centering device is reduced to a minimum. By employing a metal socket for the staff, I am enabled to employ a fastening screw to 75 connect the socket with the staff instead of an adhesive, which latter is unreliable.

Having thus described my invention, what I claim is:

In a skewer, the combination of a wooden 80 staff, a metal socket fitted on the lower end thereof and provided with a hole, a screw passed through said hole into the part of the staff inclosed in the socket, said socket being provided with an integral supporting flange 85 and a depending bearing point and also with vertical radial ribs for centering the bobbin spool.

In testimony whereof I hereunto affix my signature.

ANDREW TAYLOR.
